UNITED STATES PATENT OFFICE.

WILLIAM L. ROSS, OF JERSEY CITY, NEW JERSEY.

BUILDING CONSTRUCTION.

Application filed December 18, 1920. Serial No. 431,624.

To all whom it may concern:

Be it known that I, WILLIAM L. Ross, a citizen of the United States, residing at Jersey City, in the county of Hudson and State of New Jersey, have invented new and useful Improvements in Building Constructions, of which the following is a specification.

This invention relates to improvements in building construction, and one of the principal objects is to produce a portable device of this nature in which the frame shall be constructed of angle irons of various kinds so that the whole may be readily assembled and knocked down so that boards, metal lath or other suitable material may be quickly and firmly locked to the structure to form walls thereof.

Another object is to provide a novel corner post and improved means for connecting the various elements of the structure together.

With these and incidental objects in view, the invention consists in certain novel construction and combination and arrangement of parts, the essential features of which are hereinafter fully described, particularly pointed out in the claims, and illustrated in the accompanying drawings, in 30 which:—

Figure 1 is a perspective view of the skeleton or framework of my improved construction embodied in the form of a portable summer house.

Figure 2 is a longitudinal vertical sectional view of the same showing a portion of the wall in place.

Figure 3 is a detail view of the corner frame construction when adapted for use 40 with a shed or other roof having only a single slope.

Figure 4 is a view similar to Figure 3, but from the opposite side of the post.

Like characters of reference refer to like 45 parts in all views.

This invention contemplates the providing of a structure whereby summer houses, garages and the like may be easily and quickly erected and will be in a substantial 50 form, and yet may be readily taken apart and moved from place to place.

Referring to the drawing in detail, 10 represents the sills or base frame members which are preferably angle irons of L-shaped cross-section, and which are cut-away at 11 in the ends of their upstanding

sides at which places the side and end bars 10 overlap. Into the the cut-away portions 11 is fitted the outer corner angle bar 12 which has previously had one of its sides 60 cut-away at the ends as at 13 and the elongation 14 of the other side folded inwardly so as to fill in the end of the corner bar 12. A hole is drilled through the overlapping portions of the sills 10 and through the 65 elongation and if desired may be tapped for co-action with a screw or bolt 15 that holds these three frame members together at the corner. It is, however, easier and cheaper to use a bolt and nut and this be 70 the method of fastening in most cases.

In a similar manner angle beams or stringers 16 are secured to the upper ends of the corner posts 12. Angle beams 17 are used for rafters, and bolt against an angle 75 beam 18 which forms the ridge plate. The bolts 19 which hold the beams 16 to the corner posts 12 also pass through the upper sides of the rafters 17 at the eaves and secure these rafters in place. If desired, 80 braces 20 may be secured between the pairs of rafters.

The floor 21 may be laid on the inwardly projecting lower sides of the sills 10 and secured thereto by angle strips 22 and bolts 85 23; and the walls may be made of sheets of metal or matched lumber or any other desired material held in place by inner corner angles 24 which are secured by bolts 25.

If it is desired to have the wall in sections, T-irons 26 may be inserted at suitable places and bolted to the beams 10 and 16 and the spaces between filled in with lumber or door or window frames as may be required.

In the house construction shown in Figures 1 and 2, the inner holding angles 24 are made small; but in the shed form shown in Figure 3, the inner angle extends so as to permit passing a bolt through the inner 100 angle bar and through a corner brace 30. This form of inner corner bar is cut away in the corner as at 31 so as to make room for the nut 32 on the bolt which passes through the end of the outer corner angle. In the 105 form shown in Figure 3, the roof has but a single slope and the rafters are flattened down to fit against the top of the posts 12 so that the stringers at the ends of the structure are eliminated.

While I have described what I deem to be the most desirable embodiment of my in-

vention, it is obvious that many of the details may be varied without in any way departing from the spirit of my invention, and I therefore do not limit myself to the exact details of construction herein set forth nor to anything less than the whole of my invention limited only by the appended claims.

What is claimed as new is:—

- 10 1. A building comprising angle iron stringers and sills having portions of the ends of their upstanding flanges entirely cut away and lapped at their corners, and angle iron corner posts fitted into said portions of said sills and stringers and secured thereto.
- 15 2. A building comprising angle iron stringers and sills having portions of the ends of their upstanding flanges entirely cut away and lapped at their corners, and angle iron corner posts fitted into said portions of said sills and stringers one of the flanges of the corner posts being cut away and the other flange bent inwardly to form means for securing them to said sills and stringers.
- 20 3. A building comprising angle iron stringers and sills having portions of the

ends of their upstanding flanges entirely cut away and lapped at their corners, angle iron corner posts fitted into said portions of said sills and stringers, walls, and inner angle strips holding said walls in place against said sills and stringers and corner post.

30 4. A building comprising angle iron stringers and sills having portions of the ends of their upstanding flanges entirely cut away and lapped at their corners, angle iron outer corner posts fitted into said portions of said sills and stringers, walls, and inner angle strips adapted to be bolted in said outer corner posts to hold said walls.

35 5. A building comprising angle iron stringers and sills having portions of the ends of their upstanding flanges entirely cut away and lapped at their corners, angle iron outer corner posts fitted into said portions of said sills and stringers, walls, inner angle strips adapted to be bolted in said outer corner posts to hold said walls, and angle bar rafters secured to said stringers and to 40 an angle ridge bar to form the roof.

45 In testimony whereof I have affixed my signature.

WILLIAM L. ROSS.
